UNITED STATES PATENT OFFICE.

HENRY BREHMER, OF NEW YORK, N. Y., ASSIGNOR TO DAVID WOLFE BRUCE, OF SAME PLACE.

DESIGN FOR A FONT OF TYPE.

SPECIFICATION forming part of Design No. 18,595, dated September 11, 1888.

Application filed July 15, 1888. Serial No. 279,867. Term of patent 14 years.

To all whom it may concern:

Be it known that I, HENRY BREHMER, a citizen of the United States, residing at New York, in the county of New York and State of New York, (assignor to DAVID WOLFE BRUCE,) have invented a new and original Design for a Font of Printing-Types, of which the following is a specification.

The nature of my design is fully and clearly shown in the accompanying typographic impression, to which reference is made, in which are comprised capital and lower-case letters, punctuation-marks, numerals, and the dollar and pound-sterling symbols, all having one, or more in combination, of the features herein-after described.

The first feature is a single right line of medium light weight and varying length, shown vertically disposed in the stem-lines of the capital letters D and P and the dollar-symbol, diagonally disposed as connecting the termination of the curve-line in the capital letter S, and horizontally disposed as shown bisecting the capital and lower-case letters X and x.

The second feature is a lozenge-shaped figure, best shown in the period; also disconnected, as in the dots of the lower-case letters i and j, in the colon, and in the upper dot of the semicolon; also disconnected but with its lower angle drawn out in a slight curve, as in the comma, lower portion of semicolon, and in the apostrophe. It is shown combined with first feature singly in the capital letters A, C, D, E, L, M, N, O, Q, T, U, V, and W, lower-case letter r, and with two of figure 1 forming a right-angled figure in the cross-bar of the capital letters A and H. It is also shown in the lower-case letters b, d, f, h, i, j, k, l, m, p, q, r, u, and w, the exclamation and interrogation marks, and numerals 1 and 2, in combination with figures yet to be described.

The third feature is an elliptical curve-line with the heaviest portion of its shade toward the top and bottom of the letter, numeral, mark, or symbol and tapering inward from either or both toward its lightest portion. The true curve-line is best shown in the upper and lower halves of the cipher, to which it corre-

sponds, and with slight modification in the capital letters O and Q and the lower-case letters o and z. It is shown still further modified and variously combined in the capital letters B, (lower right-hand curve,) C, E, G, J, and T, the short and, lower-case letters c, g, s, and y, lower portions of numerals 3, 5, 6, 8, and 9, in the dollar-symbol, and in the upper curve-lines of numerals 2, 3, 6, 8, and 9 and the dollar and pound-sterling symbols.

Further modifications of the third feature are a segment of it through the heaviest portion, shown best in the right-hand limit of the capital letters M and N and the lower termination of the capital letter P with a single heavy termination, in the right-hand portions of the capital letters H and U with two heavy terminations, and in the lower-case letter i in combination with the second feature. These modifications of the third feature, with another shown in the lower terminations of the left-hand or stem lines of the capital letters H and K, are found useful in many of the capital and lower-case letters in combination one with another, or with the second feature, or with the double or serpentine curve-line shown in the upper and lower terminations of the curve-line of the capital letter D, and also one or more times, and varying in size or extent as well as in position, in the capital letters A, A, B, C, E, F, G, H, K, L, M, M, N, P, R, S, T, U, V, W, X, Y, and Z, lower-case letters a, c, s, and z, numerals 2, 5, and 7, and the pound-sterling symbol.

Minor characteristics are the curved lower terminations with dot to the stem-lines of the capital letters B and R and the upper termination of the lower-case letter l; also, the pear-shaped dot terminations to the upper right-hand portions of the capital letters V, W, and X, lower-case letters v, w, x, and y, and in the position of the cross-bar in the pound-sterling symbol; also, terminating the lengthened upper curve-lines of the capital letters I and J beyond and after their crossing of the stem-lines. Finally, a short hair-line similar to those projecting toward the right and left from the upper termination of the numeral 1, which are

common to most text letters, is used in this design, marking the connection between the lower portions of the capital letter *A* as well as the lower portions of the lower-case letters 5 *a*, *b*, *ä*, *g*, *q*, *u*, *w*, and *y*.

What I claim as my invention, and desire to secure by Letters Patent, is—

The design for a font of printing-types, as herein described, and shown in the accompanying typographic impression.

HENRY BREHMER.
